UNITED STATES PATENT OFFICE

PHILIP S. WESTCOTT, OF OAK PARK, ILLINOIS

ADAPTER

Application filed April 28, 1931. Serial No. 533,511.

The present invention relates to an adapter and particularly to one useful in connection with association with the tracks of toy electric railways for connecting dissimilar track sections and also for compensating for variations in the length of rails.

Toy electric railway systems on the market at the present time, for the most part, use a conventional pre-formed rigid type of track sections. A section of the conventional type comprises two running rails secured to the ties and a middle third rail as the live current conductor of the system. When curves are necessary, such pre-formed rigid sections are curved on fixed curvatures. Pins are inserted in the ends of the heads of some of the rails for making the electrical connection with the rails of adjacent sections. The rails utilized in making up the conventional sections are made from thin metal formed to provide a rail head substantially circular in section and hollow from end to end, webs and the usual flanges. The connecting pins enter the ends of the hollow heads of the rails for connecting the sections together in alignment and also electrically.

Letters Patent No. 1,773,560 issued August 19, 1930, disclose a toy electric railway track construction wherein the rails are flat pieces of metal removably retained in edgewise position in ties and which rails are bendable to provide curvatures of varying amplitudes.

It has been found that tracks made in accordance with the above mentioned patent have been sold for use with the conventional tracks wherein the users have desired to depart from the conventional arrangements of set-ups from that made necessary by use of the conventional track sections.

The track made in accordance with said Letters Patent will herein be designated as the "construction" type and the pre-formed rigid section heretofore described referred to herein as the "conventional" type. It will be understood, therefore, that in using these terms herein applicant uses the same in the manner named.

An object of the present invention is to provide an adapter whereby rails of the "con-

struction" type may be interchangeably used with rails of the "conventional" type.

Another object of the invention is to provide adapters for compensating for variations in rail lengths of the "construction" type.

A further object of the invention is to provide adapters for use with rails of the "construction" type for bridging the gaps occasioned when the rails of such type are used for forming curves and where inequalities occur because of such curvature, the adapters serving to connect the ends of the rails forming the gaps and at the same time to serve to bridge the gaps, thus constituting active members of the running rails of the "construction" type.

A still further object of the invention is to provide adapters whereby rails of the "construction" type may be interchangeably used with track sections of the "conventional" type, and wherein electrical communication may be established between rails of the two types easily and efficiently.

The above, other and further objects of the invention will be apparent from the following description, accompanying drawings, and appended claims.

The accompanying drawings illustrate embodiments of the present invention and the views thereof are as follows:

Figure 1 is a side elevational view of an adapter embodying the present invention.

Figure 2 is a side elevational view of a fragmental portion of track of the "construction" type showing an adapter utilized in compensating for variations in the lengths of the rail of such track.

Figure 3 is a top plan view of a fragmental portion of track of the "construction" type showing use of the adapters of the present invention in different relations. The middle rail of Figure 3 shows the adapter bridging the gap between the spaced ends of adjacent rails, while the lower rail illustrates the adapter used in connection with a filler for compensating for variations in the length of the rail occasioned by curvatures and the like.

Figure 4 is a fragmental side elevational view, partially in section, showing the adapter

in use for connecting a rail of the "construction" type with the rail of the "conventional" type.

Generally speaking, the adapter ⁵ contains plates a member which is associated in endwise fixed relation with one rail and which is engageable with another rail in endwise adjustable relation.

The drawings will now be explained.

10 The adapter illustrated consists of a flat piece of metal 1 of elongated form having an end portion 2 of reduced width and constituting a pin extension. The member 1 is provided with two bolt holes 3 punched with regard to the adjacent end of the adapter and which register with similarly punched bolt holes in the end of a rail to which said adapter may be connected. The adapter is provided with an elongated slot 4 for receiving bolts **15** anywhere in the length of the same for adjustable endwise engagement with a rail.

The rails of the "construction" type are flat pieces of spring metal arranged for removable association with ties in an endwise position. **20** Curvatures in the tracks made from these rails are formed by arranging the ties in angular relation one to another and then clamping the rails to the ties while in such relationship. Forming curvatures of whatever character necessarily affects the length of the rail sections employed in the formation of such curves. The ends of the rails of the "construction" type are punched for receiving bolts whereby splice bars or fish plates may be **25** utilized for joining together the adjacent ends of abutting rails. The bolt holes in the end of the rails are punched with definite regard to the ends of the rail as are the bolt holes 3 in the adapter 1.

30 Figure 3 illustrates ties 5 having slotted upstanding portions 6 for receiving the rails 7. The rail which appears at the top of Figure 3 is formed of two rail sections 7 of the "construction" type with the ends in abutting relation and connected by a splice bar or fish plate 8 bolted to the ends of the adjacent sections by the bolts 9, thus simulating standard railway constructions in this regard.

The middle rail of Figure 3 illustrates the **35** rail 10 as spaced forming a gap. The spaced ends of the rails 10 are connected by an adapter 1 which is illustrated as fastened to the right hand rail section 10 by bolts 11 passing through the bolt hole 3 in the adapter and registering bolt holes in the rail 10. The bolts **40** 12 pass through bolt holes in the left hand rail section 10 and through the slot 4 in the adapter. The provision of the slot 4 in the adapter allows application of the bolts 12 anywhere along the length of said slot depending on the gap existing between the **45** spaced ends of adjacent rail sections.

The lowermost rail in Figure 3 illustrates the use of an adapter where a filler plate 13 is employed to fill in the gap between the

spaced ends of the adjacent rail sections 14 and 15 which sometimes exists due to a greater curvature than usual. The filler plate 13 is fastened to the rail 14 by a splice bar 16 by means of the bolts 17 and 18. Bolt holes are formed in the splice bars 13 punched in the same manner as are the holes in the ends of the rails and also as the holes 3 in the adapter 1, that is, as regards the adjacent ends of the **50** filler plate. The adapter 1 is bolted to the end of the filler plate 13 by bolts 19 while bolts 20 pass through bolt holes in the end of the rail section 15 and the slot for the adapter.

It will thus be observed that the adapter lends itself very readily as means for compensating for variations in lengths of rails occurring when curvatures are formed from rails of the "construction" type and also serving as running rails to bridge such gaps, whereby smooth operation of the toy train **55** results.

When it is desired to use the rails of the "construction" type with sections of the "conventional" type, it is necessary to apply the **60** adapter of the present invention to the ends of the rails 21 of the "construction" type.

Figure 4 illustrates a rail of the "conventional" type where may be observed the head 22 which is hollow, the web 23, and a flange 24 together with the tie 25 secured to such **65** rail in the manner usual in the "conventional" type.

The adapter 1 is bolted by means of bolts **70** 26 to the ends of the tracks 21 of the "construction" type and then the pins 2 forming part of the adapters 1 are entered in the ends of the hollow heads 22 of the rails of the "conventional" type and pushed therein until there is tight engagement. Such engagement provides sufficient electrical connection and **75** also continuity of the heads of the rails of both the "construction" type and the "conventional" type. If desired, the ties 5 may be applied underneath the adapter in which event the set screws 27 bear against the adapter and suitably support the same.

It is understood that when rails of the "construction" type are used with sections of the "conventional" type, the "construction" **80** type is so set up as to have the ends of the running rails as well as the third rail in alignment with the corresponding rails of the "conventional" section.

Whenever the adapter is utilized for compensating for variations in the lengths of rails of the "construction" type such as illustrated in Figures 2 and 3, the adapters and splice bars are placed on the outside of such rails so as not to interfere with the flanges of the wheels of the electric train passing along the **85** track so constructed.

The invention has been described herein more or less precisely as to details, yet it is to be understood that the invention is not to be limited thereby, as changes may be made in **90**

the arrangement and proportion of parts and equivalents may be substituted without departing from the spirit and scope of the invention.

5 The invention is claimed as follows:

1. An adapter for connecting rails of the construction type of toy electric systems to rails of the conventional type, which consists in a member having a portion for connection to a rail of the construction type and a portion for entering the end of the head of a rail of the conventional type.
- 10 2. An adapter for connecting rails of the construction type of toy electric systems to rails of the conventional type consisting in a member having a portion for entering the end of the head of a rail of the conventional type and having a portion lying against the rail of the construction type, which latter portion is provided with an elongated slot for receiving bolts in the construction type rail, said slotted portion of said adapter allowing connection of a rail of the construction type with a rail of the conventional type where the 15 ends of the rails are out of abutting relation and for compensating for differences in lengths of the rails when the same are assembled in a track, the adapter serving as a running rail for the interval between the end of 20 the rail of the construction type and the adjacent end of the rail of the conventional type.
